US0D1029973S

(12) **United States Design Patent** (10) **Patent No.:** **US D1,029,973 S**
(45) **Date of Patent:** **** Jun. 4, 2024**

(54) **GOLF CLUB HEAD**

(71) Applicant: **PARSONS XTREME GOLF, LLC**,
Scottsdale, AZ (US)

(72) Inventor: **Caleb S. Kroloff**, Phoenix, AZ (US)

(73) Assignee: **PARSONS XTREME GOLF, LLC**,
Scottsdale, AZ (US)

(**) Term: **15 Years**

(21) Appl. No.: **29/847,477**

(22) Filed: **Jul. 25, 2022**

Primary Examiner — Mitchell I. Siegel

(57) **CLAIM**

The ornamental design for a golf club head, as shown and described.

DESCRIPTION

FIG. 1 is a top perspective view of a golf club head;
FIG. 2 is a bottom perspective view of the golf club head of FIG. 1;
FIG. 3 is a front elevational view of the golf club head of FIG. 1;
FIG. 4 is a rear elevational view of the golf club head of FIG. 1;
FIG. 5 is a top view of the golf club head of FIG. 1;
FIG. 6 is a bottom view of the golf club head of FIG. 1;
FIG. 7 is a left side view of the golf club head of FIG. 1; and,
FIG. 8 is a right side view of the golf club head of FIG. 1.
The broken lines shown on the drawings form no part of the claimed design.

1 Claim, 4 Drawing Sheets
